UNITED STATES PATENT OFFICE.

CLARENCE J. HAMILTON, OF PLYMOUTH, MICHIGAN, ASSIGNOR TO C. J. HAMILTON & SON, OF PLYMOUTH, MICHIGAN, A COPARTNERSHIP.

SIGHT FOR FIREARMS.

SPECIFICATION forming part of Letters Patent No. 696,962, dated April 8, 1902.

Original application filed May 13, 1901, Serial No. 59,997. Divided and this application filed January 8, 1902. Serial No. 88,886. (No model.)

To all whom it may concern:

Be it known that I, CLARENCE J. HAMILTON, a citizen of the United States, residing at Plymouth, county of Wayne, State of Michigan, have invented a certain new and useful Improvement in Gun-Sights; and I declare the following to be a full, clear, and exact description of the invention, such as will enable others skilled in the art to which it pertains to make and use the same, reference being had to the accompanying drawings, which form a part of this specification.

My invention relates to sight construction; and its object is to provide a combined front sight and muzzle-supporting band and is shown in the accompanying drawings, in which—

Figure 1 is a side elevation of the muzzle end of the rifle-barrel. Fig. 2 is a cross-sectional view.

My invention relates to that class of rifles shown in my application Serial No. 59,997, and this application is a division of the said application.

In the drawings, A represents an inner tube, which I prefer to make of brass and rifle according to the process in my Patent No. 660,725. The barrel around this inner rifle-tube is built up of a series of concentric tubes formed from sheet metal folded with the seams breaking joints.

B represents a metal strip bent and surrounding the muzzle of the barrel, with its

free ends bent outward and brought together, the two ends standing upright above the barrel, as shown at b, to form the front sight of the rifle. The contact-surfaces of these free ends may be brazed.

C is a metal reinforcing-piece provided with an elongated opening to adapt it to be slipped over the upward-extending ends that form the sight. This reinforcing-piece is forced onto the sight and may be brazed to the body of the strip surrounding the barrel. The object of this reinforcing-piece is to hold the ends of the sleeve firmly together, and thereby adapt the sleeve to form a strengthening-support at the muzzle of the barrel.

What I claim is—

1. In gun construction, the combination of the barrel and the front sight consisting of a metal band surrounding the barrel with the free ends brought together and upstanding to form a sight, substantially as described.

2. The combination of the barrel and the front sight consisting of the metal bands surrounding the barrel with its free ends brought together to form the sight in combination with the reinforcing-piece, substantially as described.

In testimony whereof I sign this specification in the presence of two witnesses.

CLARENCE J. HAMILTON.
